UNITED STATES PATENT OFFICE.

JULIUS DESSAUER, OF MAGDEBURG, PRUSSIA, GERMANY.

HORSE-COVER.

SPECIFICATION forming part of Letters Patent No. 426,780, dated April 29, 1890.

Application filed July 11, 1889. Serial No. 317,194. (No model.)

To all whom it may concern:

Be it known that I, JULIUS DESSAUER, a subject of the Emperor of Germany, residing at Magdeburg, Prussia, Germany, have invented a new Detachable and Adjustable Rain-Cover for Horses, of which the following is a full, clear, and exact description.

The usual rain-covers for horses are made of a water-proof material lined for the use in the cold season and unlined for the use in warm weather. Consequently two of such covers are always required; or, if only one rain-cover is to be used in all kinds of weather, the driver is obliged always to keep with him ready for use a second warm blanket, which is laid over the horse under the rain-cover, as the case may be. Both manners of using rain-covers present inconveniences, for the necessity of keeping two rain-covers for every horse is expensive, especially if several horses must be equipped, and if a separate blanket is used under the rain-cover it is very difficult, and it takes a good deal of time, to attach the rain-cover in such a manner on the under blanket that the former is not displaced by the movements of the horse or by the wind. Another drawback of the usual rain-covers is presented by the rigid fastening of the crupper and the straps to the same. The rigid fastening of these straps at a certain place is not suitable for all harnesses. For some harnesses it might be necessary to arrange the straps somewhat higher, and others might require them to be attached somewhat lower. Consequently a cover fit to be used with a certain harness cannot always be used with another harness.

The rigid fastening of the straps to the cover presents still another drawback—*i. e.*, that with a lateral movement of the straps the cover will also be displaced and folds will be formed which are highly prejudicial to the duration of the cover. All these deficiencies are avoided by using the new cover of my invention, which can be easily taken asunder, and is fit for use both in summer and in winter, and which, when put together, does the same service as a cover formed in one piece.

In the annexed drawings, which form a part of this specification, Figure I shows a view from beneath of my new rain-cover. Fig. I^a shows the same in position on a horse. Fig.

I^b shows a transverse section of the device as seen in Fig. I. Fig. II shows a longitudinal section and a front view of the screw-piece 55 for fastening the cover and the lining together. Fig. III shows the method of fastening the straps to the cover. Fig. IV shows a vertical section of the cover.

The rain-cover A is made of water-proof material, and on its edges a border a is arranged, which allows of the interposition of the lining B, or instead thereof of a second warm blanket. The border a, which is made rather stiff, will of course project over the 65 edges of the lining B and prevents the cover and the lining from being detached by the wind, &c.

For the purpose of fastening the lining B to the rain-cover, I use the special screw-pieces 70 C, Figs. II and III, which form at the same time the fastening-points for the necessary straps and crupper. These screw-pieces C consist of a stud d, hollow throughout its entire length and threaded both out and inside, and provided with a large head c. The stud d is inserted into the openings suitably arranged for this purpose in the rain-cover and the lining, and then an annular nut e is screwed on the stud, pressing the cover and the lining so 75 tightly together that a rigid connection of the two is obtained. If the distance between the screw-pieces C is so great that at these places the lining could be pulled out of the border, hooks can be arranged on the inside of said border, which hooks, catching the lining, fully 80 secure its remaining in position. The screw-pieces C serve also for fastening the straps D, and the latter are provided for this purpose at their ends with stud f, which are 85 screwed into the hollow studs d of the screw-pieces C, and thus fasten the straps to the cover. As the straps are made to rotate on the studs f, it is evident that they will always 90 smoothly lie on the body of the horse and prevent the formation of folds in the cover if the latter should be displaced sideways.

The crupper D', which is fastened to the cover in the same manner, can of course also easily be detached and be fastened at another point. The only thing necessary for this purpose is to unscrew the stud f and to screw the same into another hollow stud d. In the same manner the lining can be detached from the 95

rain-cover by simply screwing all annular nuts *e*, taking out the screw-pieces *C*, whereupon the lining is withdrawn from the border *a*. The rain-cover *A* is then light and 5 single, so that it can be used as a summer cover after having inserted again the screw-pieces *C* and having screwed the annular nuts *e* onto the same, whereby the border *a* is pressed against the inside of the cover *A*. 10 The straps *D* and the crupper *D'* must of course also be fastened at the proper places.

If a warm blanket is used as lining, the same can also be used as a separate horse-blanket, because it is provided with the necessary holes 15 for the screw-pieces, which, after removal from the rain-cover, can be inserted in these holes, thus allowing the adjustment of the straps and crupper. It should be understood that in this case also by a suitable adjustment of the 20 straps *D* and the crupper *D'*, one and the same blanket can be used with all harnesses. The easy removal of the lining makes it also possible to replace the same by another lining if the horse is perspiring and the first lining 25 should have become moist. This is a real novel feature of great importance for the preservation and the health of the horses. The easy exchange of the lining makes it furthermore possible to make the cover fit for 30 summer and winter and for any kind of work by the arrangement to it of the suitable linings made of linen, cotton, or wool. The special shape of the screw-pieces also makes it superfluous to arrange little leather collars 35 around the holes in the cover for the purpose of preventing the tearing of the same. The heads *c* prevent a tearing by their large projection over the cover and around the holes.

The advantages presented by my new cover 40 can be summarized as follows: First, that one and the same rain-cover can be used summer and winter, whereby the lining, if it constitutes a complete warm blanket, can also be used as a separate horse-blanket; second, that one 45 and the same rain-cover and also the lining can be used separately or combined with any kind of harness; third, that the lining can be easily exchanged if moist by reason of perspiration or rain or in accordance with the season 50 and the work; fourth, that the fastening-points for the straps and crupper can be easily

changed by the driver; fifth, that the straps will in all cases lie smoothly on the body of the horse, whereby the folding of the cover, with the ensuing wear, is prevented. 55

Having fully described my invention, what I claim as new, and desire to secure by Letters Patent, is—

1. A rain-cover for horses, consisting of a covering of water-proof material and an inner 60 covering of any suitable material for a lining, in combination with removable fastenings by which the two covering-pieces are detachably connected together, substantially as described.

2. A cover for horses, consisting of an outer 65 covering and an inner covering-piece, in combination with removable fastenings by which the two coverings are detachably connected together, and with the crupper and girth-band carried by said fastenings, substantially as 70 described.

3. A cover for horses, consisting of an outer and an inner covering-piece, a binding passing around the outer edges of said covering-pieces, and a series of removable fastenings 75 for securing said coverings together, substantially as described.

4. In a rain-cover for horses, the lining *B* and the cover *A*, combined with a border *a*, arranged on the cover, the securing-straps and 80 crupper, and screw-pieces *C*, forming at the same time the fastening-points for the straps and crupper, substantially as and for the purpose hereinbefore described and set forth.

5. A cover for horses, consisting of an outer 85 covering and an inner covering-piece, in combination with removable fastenings having threaded sockets, by which fastenings the two coverings are detachably connected together, securing straps or cords, and screws independent of and separate from said fastenings, but adapted to fit said sockets, whereby said straps may be secured and adjusted irrespective of the securing of the two coverings, substantially as set forth. 90

In witness whereof I have hereunto set my hand in presence of two witnesses.

JULIUS DESSAUER.
